ADJUSTABLE OTTOMAN

Carl Fuerst, Bronx, N. Y., assignor to Gleitsman's Inc.,
Long Island City, N. Y., a corporation of New York

Application April 11, 1957, Serial No. 652,214

2 Claims. (Cl. 155—169)

The present invention relates, in general, to ottomans, and in particular to ottomans having adjustable seat members.

Ottomans of the general type to which the present invention relates are disclosed in the copending applications of Harold Gleitsman and Carl Fuerst, Serial Number 591,228, filed June 13, 1956 and Serial Number 636,646 filed January 28, 1957, in the copending application of Carl Fuerst, Serial Number 646,039 filed March 14, 1957, and in the copending application of Harold Gleitsman, Serial Number 646,040 filed March 14, 1957, all of which are assigned to the assignee hereof.

An object of the present invention is the provision of an ottoman of the backless seat or bench type which has a relatively simple and efficient device for adjusting the tiltable seat to different tilted positions thereof.

Another object is the provision of a relatively inexpensive and simple device which will convert any conventional chair or seat into a posture chair and which will not interfere with the decor or decorative scheme of furniture used in the particular room in which said device may be used.

A further object is the provision of a highly novel backless seat of the bench type which can function either as an ottoman or for converting a conventional chair into a posture chair.

The above and other objects, features and advantages of the present invention will be more fully understood from the following description considered in connection with the accompanying illustrative drawings.

In the drawings which illustrate the best mode presently contemplated of carrying out the invention:

Fig. 1 is a perspective view of a posture chair or seat formed by the ottoman of the present invention in association with a conventional chair;

Fig. 2 is a side view of the ottoman with the seat thereof in its lowered or closed disposition;

Fig. 3 is a plan view taken on the line 3—3 of Fig. 2;

Fig. 4 is a sectional view, on an enlarged scale, taken on the line 4—4 of Fig. 2 and illustrates the seat in a raised or tilted disposition thereof;

Fig. 5 is a fragmentary sectional view taken on the line 5—5 of Fig. 4;

Fig. 6 is a view similar to Fig. 2 and illustrates a modification;

Fig. 7 is a fragmentary sectional view, on an enlarged scale, taken on the line 7—7 of Fig. 6, with parts broken away for purposes of illustration;

Fig. 8 is a sectional view, on an enlarged scale, taken on the line 8—8 of Fig. 6, with the seat being illustrated in a raised or tilted disposition thereof;

Fig. 9 is a fragmentary view similar to Figs. 2 and 6 and illustrates an additional modification; and

Fig. 10 is a sectional view, on an enlarged scale, taken on the lines 10—10 of Fig. 9.

Referring now to Figs. 1 through 5 of the drawings in detail, there is shown in detail an ottoman 10 pursuant to the present invention. The ottoman 10 is in the form

2

of a bench or backless seat. More specifically, the seat 10 has an open framework base constituted by a pair of interconnected U-shaped tubular frame or end members 12 and 14. Each U-shaped member is provided with the opposing legs 16 and 18 which are interconnected by a handle-defining cross-piece 20. The paired legs 16—16 constitute the front legs of the bench 10 and the paired legs 18—18 constitute the rear legs thereof. Each leg is provided with a cup 22 of rubber or other non-skid material.

The rear legs 18 are interconnected by the tubular rods, cross members or struts 24 and 26 suitably secured thereto. The opposite ends of the lower strut 24 are flattened, as at 32, as best shown in Fig. 5, and are force-fit into complementary slots 28 defined adjacent the lower ends of the legs 18. It will be understood that the opposite ends of the upper strut 26 are similarly flattened and force-fit into similar slots defined adjacent the upper ends of the legs 18. The front legs 16 are interconnected by the tubular rod, cross member or strut 34, the opposite ends of the latter being secured in the legs 16 in the same manner as described for the securement of the rods 24 and 26 to the rear legs 18.

Provision is made for a bench top or seat and foot rest 36 which may be provided with suitable padding material and which may be upholstered in suitable fabrics or plastic material. Pursuant to an important feature of the present invention, the bench top or seat 36 may be locked in various tilted or oblique positions thereof in a highly novel manner. In this connection, the seat 36 is mounted for pivotal movement by the front strut or rod 34, between the legs 16—16, provision being made for a pair of laterally spaced brackets 38—38 secured to the lower surface 42 of the seat, as best shown in Figs. 3 and 4. The rod 34 is secured by said brackets to the seat with the brackets 38 rotatable relative to the rod 34 so that the seat member 36 may be pivoted about the rod 34. The seat 36 is also provided at its undersurface 42 and adjacent the side thereof opposite the side adjacent to which the brackets 38 are secured, with an additional pair of laterally spaced brackets 44—44. The brackets 44 pivotally mount a rigid brace or retaining assembly 46 which is utilized to releasably retain the seat member 36 in a plurality of different adjusted tilted positions thereof.

The assembly 46 is constituted by a pair of opposing vertically extending elements 48—48 which are interconnected by the vertically spaced cross members 50. The upper ends 52—52 of the vertical elements 48 are inwardly directed relative to the assembly 46, said ends being in confronting relation. Said end portions 52 are mounted for rotary movement in the associated brackets 44 and constitute the pivots for the assembly 46. The lower end 54 of each element 48 is bent upwardly to form an upwardly directed hook, the function of which will presently appear. The cross members 50 are suitably secured to the elements 48, as by welding or soldering, and straddle the laterally spaced vertically extending elements 48. More specifically, the opposite ends 56 of each cross element 50 is formed into a downwardly directed hook in contradistinction to the upwardly directed hooks 54 provided at the lower ends of the vertical elements 48. The lower hooks 54 serve to lock the ottoman 10 with the seat 36 in horizontal condition thereof for utilization as a backless or bench type seat. More specifically, and as best shown in the broken line position of the seat 36 in Fig. 4, it will be noted that the forward end of the seat rests on cross member 26 and the hooks 54 engage under the lower strut 24 so as to releasably lock the seat member 36 in its closed or seat defining position. However, when it is desired to utilize the ottoman 10 as a footrest in connection with a conven-

tional chair C so as to form a posture or health chair, as best illustrated in Fig. 1, the hooks 54 are disengaged from the lower strut 24 by pivoting the assembly 46 outwardly of the position thereof illustrated in Fig. 2 and in broken line in Fig. 4. With the hooks 54 disengaged from the strut 24, the seat 36 may be pivoted about the strut 34 as illustrated in Fig. 4. In order to releasably retain the seat 36 in a desired adjusted or oblique foot-rest position thereof, the associated pair of hooks 56 of the assembly 46, adjacent the upper strut 26 for the desired degree of tilt of the seat 36 are engaged on the strut 26. In the present embodiment, the seat 36 may be adjusted to three different tilted or foot-rest positions thereof above its seat defining position as shown in broken line in Fig. 4. In the full line position of the seat 36, the lowermost pair of hooks 56 are engaged on the upper strut 26 to represent the maximum tilted position of the seat 36, it being understood that when the intermediate set of hooks 56 engage on the strut 26, the seat 36 will be lowered to an intermediate tilted position and with the uppermost hooks 56 engaged on the strut 26, the seat 36 will be in its minimum tilted or adjusted position. With the seat 36 in its lowermost or closed position, it will be noted that the three sets of hooks 56 extend between the struts 24 and 26 with the bottom hooks 54 engaged under the strut 24.

Referring now to Figs. 6 through 8 in detail, there is shown an ottoman 10A which is similar in all respects to the previously described ottoman 10 except that the number of pairs of hooks 56 is reduced to one pair and the number of cross members or struts between the front legs 18 is increased. More specifically, between the lower strut 24 and the upper strut 26, as previously described, there is now provided two additional struts 58 and 60 which are equally spaced between the struts 24 and 26 and which are secured, in the same manner as the latter, to the paired legs 18—18. In the present embodiment, the detent or retainer assembly 46A is similar in all respects to the previously described retainer assembly 46 except that provision is made for one cross member 50 only between the vertical elements 48. Only the lowermost cross member 50 is retained, the two upper cross members 50 being obviated in the detent assembly 46A. The vertical elements 48A are slightly changed from the previously described vertical elements 48 in order to permit the hooks 56 on the detent assembly 46A to engage any of the three upper struts 26, 58 and 60. More specifically, and as best shown in Fig. 7, the vertical elements 48A are provided with previously described confronting pivot portions 52 which are offset or curved outwardly, as at 62, to provide the necessary clearance for the vertically disposed portions of the elements 48A, as will be readily apparent.

The ottoman 10A functions substantially in the same manner as the ottoman 10, the locking hooks 54 being released from the lower strut 54 in order to tilt or pivot the seat element 36. Thereafter, in order to retain the seat 36 in a desired adjusted or tilted position thereof, the single pair of hooks 56 are engaged over the strut at the desired level above the lowermost strut 24. For example, as shown in Fig. 8, the seat 36 is in the maximum tilted position thereof, with the single pair of hooks 56 engaged over the uppermost strut 26.

Referring now to Figs. 9 and 10, there is illustrated an ottoman 10B pursuant to an additional modification. The ottoman 10B is similar in all respects to the previously described ottoman 10 except for the construction of its detent or retainer assembly 46B. More specifically, in accordance with the present embodiment of the invention, the previously described hooks 56 of the retainer assembly 46 are formed integral with the vertical elements 48 thereof. As here shown, the vertically extending elements 48B of the retainer assembly 46B are provided with the previously described confronting pins 52 engaged within the brackets 44. However, each hook

56A of the detent assembly 46B is formed, as best shown in Fig. 10, by bending the material of each member 46B back upon itself to form the three vertically spaced hooks 56A, and the lower end of said element 46B is provided with the previously described bent up hook 54. A single cross member 64 extends between and is engaged to the vertical elements 48B so as to constitute a hand grasp for manipulating the detent assembly 46B. In all other respects, the ottoman 10B is similar to the ottoman 10A and functions in exactly the same manner so as to constitute either a backless or bench type seat or an adjustable foot rest for use with a conventional chair C.

While I have shown and described the preferred embodiments of my invention, it will be understood that various changes may be made in the present invention without departing from the underlying idea or principles of the invention within the scope of the appended claims.

Having thus described my invention, what I claim and desire to secure by Letters Patent, is:

20 1. An ottoman bench comprising a base and a foot rest member pivotally mounted on said base and adapted to lie in a horizontal position or in a tilted leg-supporting position; the base being a unitary framework adapted to provide a suitable support and comprising a pair of front legs, a first horizontal cross member connecting and rigidly uniting the front legs, a pair of rear legs, a plurality of vertically spaced horizontal cross members extending between and rigidly uniting the rear legs, a substantially horizontal member extending from a front leg to a rear leg on each side of the ottoman bench and connecting and rigidly securing the two pairs of legs; the pivot mounting of the foot rest member being underneath the foot rest member and uniting the latter to the first named horizontal cross member; rigid brace means pivotally mounted at its upper end on the under side of the foot rest member at the rear of the base, and means on said rigid brace means for partially embracing and seating, selectively, on each of a plurality of said vertically spaced horizontal cross members, respectively, said seating means being manually engageable with and releasable from the selected horizontal cross member, and the rigid brace means being of such length as to support said foot rest member in said tilted position when said seating means is seated as aforesaid, said brace means also having a part releasably engageable with one of said vertically spaced horizontal cross members for releasably preventing substantial upward pivotal movement of said foot rest member when the latter is in said horizontal position.

2. An ottoman bench adapted to be positioned adjacent the front of a chair, and comprising a base and a foot rest member pivotally mounted on said base and adapted to lie either in a horizontal position or in a tilted leg-supporting position; the base being a unitary framework adapted to provide a suitable support and comprising an open frame having a pair of front legs, a first horizontal cross member connecting and rigidly uniting the front legs, a pair of rear legs, a second horizontal cross member connecting and rigidly uniting the rear legs, a substantially horizontal member extending from a front leg to a rear leg on each side of the ottoman bench and connecting and rigidly securing the two pairs of legs, said foot rest member having an upper padded surface, and the pivot mounting of the foot rest member being underneath said padded surface and uniting the latter to the first named horizontal cross member, rigid brace means pivotally mounted at its upper end on the under side of the foot rest member at the rear of the base, and means on said rigid brace means for seating on the second horizontal cross member at the rear of the base, said seating means comprising a plurality of vertically spaced transverse parts selectively engageable with and releasable from the second horizontal cross member to support said foot rest member in adjusted tilted position when said seating means is seated on said second cross member,

said seating means being manually engageable with and releasable from said second cross member by pivotal movement toward and away from said second cross member at the outer side of the frame and being gravity biased into engagement with said second cross member. **5**
